CLAIM

We claim the ornamental design for a magazine pouch, as shown and described.

DESCRIPTION

FIG. 1 is a perspective view of a magazine pouch showing the new design;

FIG. 2 is another perspective view thereof;

FIG. 3 is yet another perspective view thereof, shown with two magazines held therein;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines of the magazines illustrate environment that form no part of the claimed design. All other broken lines illustrate features of the magazine pouch that form no part of the claimed design.

1 Claim, 8 Drawing Sheets
